BOBBIN STRIPPER.

William V. Goodhue and Robert E. Morton, Warwick, R. I., assignors to Universal Winding Company, Boston, Mass., a corporation of Massachusetts

Application May 3, 1951, Serial No. 224,382

30 Claims. (Cl. 28—19)

1

This invention relates to bobbin-stripers for removing the residue of weft or filling yarn remaining on bobbins ejected from the running shuttle of a loom after the service winding has been exhausted. This application is a continuation-in-part of our previous application Serial No. 112,362, filed August 25, 1949.

The present invention consists in modifications and improvements in the device of our prior application.

The main object of the invention is to provide an automatically-operated bobbin-stripper for receiving spent bobbins discharged from the shuttle of a loom, removing the yarn remaining thereon after the exhaustion of the service winding, and delivering the stripped or denuded bobbins to a conveyor for transporting them to a winding machine to fill them again with weft or filling yarn.

One object of the invention is to simplify the construction of the device and render it more economical to manufacture.

Another object is to increase the efficiency of the device and render it more dependable in action.

Another object is to provide means in the stripper for caliperizing the bobbins after a stripping operation to test them for any yarn remaining on the bobbins whereby they may be segregated from the completely stripped bobbins.

Another object is to provide in a bobbin-stripper of the type indicated means for delivering completely stripped bobbin to one compartment or receptor and preventing partially stripped bobbins from delivery to the same compartment by transferring them to a separate compartment.

Another object is to provide caliperizing means for detecting any yarn that may remain on a bobbin after the stripping operation with means for collecting incompletely stripped bobbins in a compartment in the stripper separate from the compartment for receiving the completely stripped bobbins.

Another object is to provide in a bobbin-stripper of the type indicated means for releasing completely stripped bobbins into a chute to deliver them to a certain compartment of the stripper for transport therefrom and means for delivering incompletely stripped bobbins into another chute to transfer them to a separate compartment.

Another object is to provide efficient means for holding the end of the trailing yarn from a bobbin entering the stripper and attaching it to a rotary drum or mandrel for winding it thereon to strip the bobbin.

2

Further objects of the invention are set forth in the following specification which describes a preferred form of construction of the bobbin-stripper and its operating elements as illustrated by the accompanying drawings. In the drawings:

Fig. 1 is a front elevational view of the complete bobbin-stripper shown in reduced scale;

Fig. 2 is a greatly enlarged end elevation of the device with the walls of its casing shown partly in section or broken away;

Fig. 3 is a plan view of the stripper showing the means for engaging the length of yarn trailing from a bobbin entering the stripper and carrying it to the rotary drum or mandrel for attachment thereto to be wound thereon;

Fig. 4 is a still further enlarged plan view of one compartment of the casing, illustrated partly in section, and showing the caliperizing means for detecting any excess yarn left on an incompletely stripped bobbin while another bobbin is being stripped, and a third bobbin held on the perch after it has been entered into the casing;

Fig. 5 is a similar plan view showing a bobbin being moved into stripping position, a completely stripped bobbin entering one chute for delivery to a transfer compartment of the casing, and a third partly stripped bobbin entering a different chute for delivery to a separate compartment to segregate it from the completely stripped bobbins;

Fig. 6 is a detailed plan view showing the means for catching the bobbin as it descends into the stripper and guiding it to maintain it in erect or vertical relationship; and

Fig. 7 is a detailed view of the means for holding the bobbin in stripping position within the casing and also the means for severing the length of yarn trailing from an incompletely stripped bobbin as it is being tested by the caliperizing means.

In automatic looms as commonly employed in the weaving art the filling or weft yarn is supplied from bobbins carried by thrown shuttles and upon substantial exhaustion of the yarn on each bobbin, filling-changing mechanism operates automatically to eject the spent bobbin from the shuttle and substitute a full bobbin so that the loom may continue to weave without interruption as the filling is supplied by reserve bobbins transferred from either a rotary battery or a vertical magazine. The transfer mechanism of the loom operates to force a new bobbin down into the shuttle as the latter is boxed at the end of the lay, thereby driving out the spent bobbin which is ejected through an opening in the bottom of

the shuttle, thence to be caught in a receptacle placed therebelow. For use in automatic looms the bobbins are wound with an initial length of reserve yarn, termed a "bunch," to insure against the filling running out before the bobbin is changed in the shuttle, which otherwise would cause "mispicks" in the cloth being woven. Feeler-motions are provided for testing the yarn in the shuttle at each pick and when the service winding on the bobbin is exhausted, or substantially so, the feeler engages with the bobbin to initiate the operation of the filling-changing or transfer mechanism and supply a fresh bobbin to the shuttle as it is boxed at the end of the lay.

It is obvious that when the spent bobbins are ejected from the shuttle carrying a residue of yarn thereon remaining in the bunch they cannot be rewound over the bunch since the yarn must be continuous from the bunch to the service winding in order for the filling change to be made without a break in the yarn as it is woven into the cloth. Heretofore, it has been a common practice to remove the spent bobbins from the loom and convey them to another location whereby, by means of a bobbin-stripper, the bunch-winding may be unwound or otherwise removed from the bobbin to prepare it for rewinding. In some cases the bunch is stripped by cutting through the coils of yarn with a knife or other sharp instrument, but this practice is objectionable as the knife is liable to slit the barrel of the bobbin and mutilate it so that the yarn will not deliver freely therefrom. Various types of bobbin-stripers have been devised for removing bunch-windings from bobbins, but in most cases they require manual operation and are not entirely satisfactory in practice. It is therefore an important object of the present invention to provide a bobbin-stripper that is entirely automatic in its operation and can be applied directly to the loom to be driven thereby and to operate in synchrony with the filling-changing mechanism thereof for continuously receiving the bobbins as they are ejected from the loom-shuttle, stripping the residual yarn therefrom, and transporting the denuded bobbins to the winding machine where they can be rewound with a new bunch continuous with the service winding.

A particular object of the present invention, as before stated, is to provide means for preventing bobbins containing yarn after the stripping operation from being carried to the winding machine for rewinding filling thereon; the invention of our U. S. patent application Serial No. 159,814 embodying the stripper combined with an inbuilt automatic bobbin-winder in the loom for furnishing wound filling bobbins directly to the shuttle of the loom. In most cases the device of our application referred to above strips all the residual yarn from the bobbin, but in rare instances bobbins containing an amount of yarn in excess of the bunch may be received in the stripper through accident or otherwise. For example, due to improper operation of the loom the shuttle may bounce when boxed at the end of the lay, in which case the feeler mechanism will act to initiate the operation of the filling-changing or transfer means so that the bobbin is ejected before all the filling in the service winding is used. As another example, the yarn in the bunch may be improperly wound to cause it to snag and break while being stripped from the bobbin and in such instances the stripper cannot operate successfully to remove all the filling from the bobbin. To insure against such contingencies the present in-

vention provides means for testing each bobbin after the stripping operation and discarding or segregating bobbins which are not completely stripped so as to prevent them from being returned to the winding machine for rewinding.

Referring to the drawings, the present improved bobbin-stripper is herein shown as comprising a compartmented casing 2 constructed substantially of sheet-metal plates for the sake of economy in cost of manufacture and adapted to be attached to, or built into, the structure of a conventional type of loom. As shown in Figs. 1 and 2, the casing 2 may comprise an upper box-like section divided transversely into two compartments 3 and 4 by means of a removable vertical panel 5; the main or rearward compartment 3 being employed for receiving and holding the bobbins to be stripped and the separate forward compartment 4 for collecting waste yarn stripped from the bobbins. The waste-collecting compartment 4 may have a front cover-plate 6 hinged to the bottom at 7 and normally latched at the top, but adapted to be swung outwardly to open the compartment, as shown in Fig. 2, for removing the waste yarn therefrom.

The upper section of the casing 2 may be mounted above a horizontally-extending box-like section 8 with openings in the bottom through which the completely or incompletely stripped bobbins are discharged into two separate chutes therebelow. A vertical wall 9 inclined rearwardly at the top forms a restricted passage through which the bobbins descend into the compartment 8. The main chute 10 for stripped bobbins has a curved bottom with upstanding sides and extends downwardly into a rectangular compartment 11 for receiving the completely stripped bobbins. The compartment 11 may be suspended from the casing 8 by means of bolts 12 inserted through flanges 13 as shown in Fig. 1, and mounted therebelow or formed as a part thereof is another compartment or receptor 15 for incompletely stripped bobbins. The last-mentioned compartment 15 encloses the greater portion of the chute 10 and extends therebelow in the form of a tray having an inclined bottom wall 16 as shown in Fig. 2. The compartment 15 is for receiving the incompletely stripped bobbins which roll down towards its forward end and may be removed manually from its lower tray portion through its upper open front. The chute 10 is generally of cradle-shape having flanges 17 at the top fastened to the bottom flanges of the compartment 8 by bolts 18 with its main portion entering through a rectangular opening 19 in the side of the lower compartment 15. Above the mouth or opening of the chute 10 its bottom wall is extended upwardly in a flange 21 for guiding the bobbins down onto its sloping bottom.

As in the device of our earlier patent application referred to above, a conveyor-belt 20 reaches down into the interior of the compartment 8 and passes around a flanged pulley 22 that is driven by means later described to travel one length of the belt upwardly to another location; for example, to the automatic filling-bobbin winder incorporated directly in the loom structure. As described in our prior application and shown in Fig. 1 of the present drawings, the conveyor-belt 20 carries one or more permanent magnets 24 suspended from ears 25 on the belt 20 to adapt them to be carried down into the chute 10 for making contact with the metal rings *r* on the bobbins *b* so as to lift the stripped bobbins out of the chute and convey them to the winder in the manner and for the purpose explained in our application

Serial No. 159,814, filed May 3, 1950, which relates to automatic bobbin-supply means for automatic looms. It will be understood that the horizontal compartment 8 is open at the top at 21 for the passage of the belt 20 therethrough with its suspended magnets and the stripped bobbins carried thereby.

It has been stated that the bobbins are calipered for testing them to detect any residual yarn thereon after the stripping operation so that incompletely stripped bobbins may be segregated in a separate compartment. For this purpose a secondary chute 30 is located above the chute 10 with its curved bottom wall formed at the end with an angular projection 31 for forcing the partially stripped bobbins laterally to cause them to roll off therefrom and drop down at the side of the main chute 10 into the lower compartment 15 in a manner more fully explained hereinafter.

The upper or secondary chute 30 is provided with a tubular hinge 32 at one side, see Fig. 2, through which extends a pin 33 held in ears 34 at the end of a hinge member 35 fastened to the web of the channel-iron 83 which forms one side of the lower compartment of the casing 2. The hinge 35 permits the chute 30 to swing upwardly should a bobbin passing into the main chute 10 engage therewith due to crowding of the bobbins in case of improper operation of the device. This construction is provided as a precautionary measure so that the bobbins will not jam or stick in the chute 10 and become inaccessible for manual removal. The chute 30 is normally held in operative position by a lip 36 projecting forwardly from the member 35 against which the chute rests. Should the chute be rocked or tilted upwardly by crowding of the bobbins, immediately upon its release it will drop back into operative position by the action of gravity.

The compartmented casing 2 of the stripper may be mounted on the loom by attaching it to one of the legs L thereof as shown in Fig. 1. For this purpose a vertical plate 38 is bolted to the reinforced end flange 39 of the section 8. A plurality of studs 40 projecting horizontally from the plate 38 are inserted through openings in the web of the leg L and set up against the web to support the whole casing from the loom frame.

Referring to Fig. 2, the present stripper, as in that shown in our prior application, embodies a rotary drum or mandrel 45 fast on a horizontal shaft 46 which is journaled in a bearing 47 formed as part of a bracket 48 fastened to a portion of the casing 2. At the rear of the mandrel 45 is a relatively fixed cylindrical cam 50 formed on its periphery with a helical spline or rib 51 which is engaged in slots 52 at the ends of a plurality of reciprocable fingers 55. The fingers 55 are slidably held in slots on the periphery of the mandrel 45, the construction and arrangement of these parts being similar to that shown in our prior application to adapt the fingers to be reciprocated for pushing the coils of yarn off from the periphery of the mandrel 45 to discharge the waste into the forward compartment 4 of the casing 2. As shown in Fig. 2, the forward ends of the fingers 55 are undercut at 56 to provide spaces for the yarn to enter for attaching its end to the mandrel 45 as the bobbins enter the stripper. The forward tapered portion of the mandrel 45 projects through an opening 57 in the panel 5 that forms the partition between the compartments 3 and 4.

Above the mandrel 45 is a disk 60 carried by a vertical shaft 61 for rotation above a horizontal plate 62, see Fig. 3, formed as a part of the bear-

ing bracket 48. The disk 60 is driven by a worm 64 meshing with a helical gear 65 on its shaft 61, the worm 64 being carried by or formed on a horizontal shaft 66 journaled in a bearing 67 formed as a part of the bracket 48. The shaft 66 carries a grooved pulley 68 fast on its outer end which is connected by a belt 69 to a grooved pulley 70 fast on the mandrel shaft 46. The mandrel shaft 46 also carries a larger pulley 71 fast thereon and connected by a belt 72 to a lower pulley 73 carried by a shaft 75, see Figs. 1, 2 and 3. The shaft 75 is journaled in a bearing 76 at the end of a curved arm 77 supported by a quadrant 78 which is adjustably mounted on a bracket 79 by means of a bolt 80. The bracket 79 is bolted at 81 to a channel-iron 82 forming part of the rearward wall of the casing compartment 8; a corresponding channel-iron 83 extending horizontally to form the front wall of the casing at this location. The shaft 75 carries a pinion 85, see Fig. 2, meshing with a gear 86 fast on a shaft 87 journaled in a bearing 88 on the bracket 79. The shaft 87 has fast thereon the pulley 22, see Fig. 3, for traveling the conveyor-belt 20, previously referred to, which carries the magnets 24 for lifting the stripped bobbins out of the lower compartment 15, see Fig. 1. The belt 12 passes from the pulley 73 to a larger pulley 90 driven from the power means of the loom, later described. The pulley 90 is carried on a shaft 91 journaled in a bearing 92 on a bracket 93 fastened to the channel-iron 82 as indicated in Fig. 2, but not herein shown in detail.

The rotary disk 60, referred to above, carries a plurality of spring-fingers 100 attached to its periphery, see Figs. 1 and 3. The fingers 100 are faced with strips 101 of resilient material such as rubber, felt or the like and are adapted to be flexed arcuately as they are carried around by the disk 60. As shown in Fig. 3, the end of one finger 100 wipes against the side of the casing 2 during its revolution by the disk 60 while the opposite finger 100 makes contact with a vertical blade 103 having its foot 104 fastened to the top of the horizontal shelf 62 on the bracket 48 as shown in Fig. 2. The fingers 100 are revolved above the plate 62 to cause one or the other to engage with the yarn trailing from a bobbin as it enters the stripper and carry it across the drum or mandrel 45 located therebelow for attachment thereto as the yarn is drawn in under the slotted ends of the fingers 55.

Mounted above the rotary disk 60 is a relatively flat brush 105 held with its bristles inclined upwardly as shown in Fig. 2. The bristles are fastened in a tube 106 held in an enclosing member 107 formed with ears 108 and 109 at its opposite ends for holding it in place. A cotter pin 110 projecting through a hole in the end wall of the casing 2 and hooked through a hole 111 in the ear 108 of the member 107 pivotally secures the brush to the casing under the tension of a spring 112. The adjacent end of the spring 112 is hooked through a hole in the other ear 109 as shown in Fig. 3. The opposite end of the spring 112 is hooked through a loop 113 in a blade 114 having its foot secured to the top of the plate 62. The spring 112 is tensioned slightly between the brush 105 and the blade 114 so that its twisting torque will rock the mounting member 107 slightly to incline the bristles upwardly. The brush 105 is employed for catching the end of the yarn trailing from a bobbin as the latter drops through the bristles in entering the casing 2 from a chute 115.

The chute 115 is of substantially hood-shape and mounted above the upper section of the casing 2 with its lower portion projecting downwardly into the open top of the compartment 3 to adapt it to receive bobbins ejected from the loom-shuttle to guide them into the stripper, see Fig. 1. As the bobbins fall through the chute 115 into the compartment 3 their descent is guided to maintain them in vertical position as they drop onto a pivoted rest or perch 120, see Fig. 7, which is constructed and arranged substantially like that shown in our prior application first referred to above.

The perch 120 is pivoted on a pin 121 held in the sides of a bifurcated bearing member 122 at the lower end of a sheet-metal arm 123. The upper end of the arm 123 is formed with ears 124 pivoted on a pin 125 extending between the sides of a folded sheet-metal bearing member 126, see Figs. 5 and 7, fastened to the outer side of the casing 2 by means of bolts 127 in its laterally-extending flanges 128. A helical spring 130 surrounding the pin 125 is held with one end 131 underlying one side of the bearing member 126 with its opposite end 132 engaging against the arm 123 to maintain it in vertical position parallel with the side of the casing 2. The pivoted rest or perch 120 is formed with a depending keel-like portion 135, the forward edge of which is engageable by a reciprocating slide, later described, so as to tilt the arm 123 clockwise, as viewed in Fig. 7, and withdraw the perch rearwardly from under the bobbin to adapt it to drop onto a floor or deck 140 extending across the interior of the casing 2. The perch 120 operates in substantially the same manner as that explained in our application for patent first above referred to being normally maintained in the position shown in Fig. 7 and slightly inclined upwardly under the control of a relatively light helical spring 136 surrounding its pivot-pin 121.

Before reaching the perch 120 the enlarged head at the butt end of the bobbin b makes contact with a horizontal shelf 145 pivoted on a pin 146 in the bearing member 126, previously referred to. The main portion of the shelf 145 projects through an opening in the side of the casing 2 and its rearward portion is bent downwardly at 147 with a weight 148 fastened thereto. The weight 148 tends to maintain the rearward end of the shelf 145 bearing against the edge of the rearward wall 149 of the sheet-metal bearing member 126 with the shelf projecting horizontally into the compartment 3 of the casing 2. The forward end of the shelf 145 is slotted to form a re-entrant opening or mouth 150 for receiving the barrel of the bobbin b as the shelf is swung downwardly into the relationship shown in Fig. 1. Fastened to the under side of the shelf 145 is a right-angular member 151 having a downwardly-projecting arm 152 bent angularly at its end and formed with a rounded mouth or opening 153 therein, see Figs. 6 and 7. When the butt end of the bobbin strikes the shelf 145 it will tilt it downwardly about its pivot-pin 146 until the angular end of its arm 152 strikes against the side of the casing 2 as shown by dotted lines in Fig. 1. As the shelf 145 is tilted downwardly the bobbin b will slide off from the shelf and its barrel will enter the mouth 150 at the end thereof. In this way the bobbin is guided to maintain it in upright or vertical relationship as it drops onto the perch 120.

Referring to Fig. 6, means are provided for engaging the butt end of each bobbin b after it drops off from the perch 120 to advance it along

the deck 140 and fixedly clamp it in erect position for stripping. As in the construction and arrangement of the stripper disclosed in our prior application for patent first referred to above, a pusher or ejector 155 is slidably mounted for reciprocation in a U-shaped guide-member 156 mounted on the floor 140 at the rear of the compartment 8. The pusher 155 is in the form of a rectangular bar 154 to the end of which is fastened a laterally-extending sheet-metal arm 157 having an upwardly-projecting folded portion or finger 158 at its forward end. The pusher or slide 155 is provided with a pin 159, see Figs. 5 and 7, projecting rearwardly from the bar 154 through a longitudinal slot 160 in the rear wall 82 of the casing 2 and pivotally connected to a link 161, the opposite end of which engages a crank-pin 162 on the arm 163 of a rotary member 165 on the shaft 91, previously referred to.

The shaft 91 has fast thereon a bevel-gear 166 meshing with a similar gear 167, see Figs. 2 and 3, on a shaft 170 journaled in bearings 171 and 172 on the bracket 93, previously mentioned. The shaft 170 carries a one-way clutch-member 175, not herein shown in detail but of any suitable construction as usually employed. The clutch-member 175 is actuated to continuously rotate the shaft 170 by means of a pair of oscillatable arms 176 and 177 pivotally connected to oppositely-extending radial arms 178 on said clutch-member, one of which is shown in Figs. 2 and 3. The arms 176 and 177 may be oscillated from the motion of the lay-sword 1, being pivotally connected to a pin 180 on a member 181 fastened to the sword by clamps 182 projecting through a plate 183 and held by nuts 184.

The bobbin b to be stripped is advanced into the clamping means by engagement therewith of the pusher 155 as it is slid toward the right by the link 161, as viewed in Fig. 5. The clamping means comprises a sheet-metal plate-member 190 having a flange 191 fastened by bolts 192 to the forward wall 83 of the casing 2. The plate 190 has one portion 193 bent rearwardly and upwardly at an angle to a vertical plane with its inclined folded portion adapted to guide the bobbins laterally as they drop from the perch 120. The remaining flat portion of the plate 190 is arranged with its edge 194 engageable with the head of the bobbin b as it rests on the floor 140 in the casing 2. Mounted in the casing 2 is a wire spring 195 formed with a central straight portion 196 for engaging between the two upper steel rings r on the head of the bobbin b and angular leg portions 197 and 198 projecting therefrom at its opposite ends. One leg 197 is secured fast by a screw 199 extending through a loop at its end and secured in the rearward wall 82 of the casing 2. The opposite leg 198 of the spring 195 is bent outwardly to form an arcuate portion adapted to engage against the rearward wall 82 of the casing 2 and to slide therealong as the spring is compressed. The bobbin b being advanced into stripping position rides along the inclined leg 197 of the spring 195 and compresses the spring as the straight portion 196 thereof engages between the two upper steel rings r on the head of the bobbin, see Figs. 4 and 7. The bobbin is thus clamped in position between the spring 195 and the edge 194 of the plate 190 to hold it fixedly during the stripping operation.

The caliper means for testing each bobbin to detect any yarn remaining thereon after a stripping operation is constituted and arranged

as follows: Extending longitudinally within the section 3 of the casing 2 is an upstanding blade or plate 203 having its foot 204 welded or otherwise fastened to the floor 140. The plate 203 has a horizontal flange 205 at the top projecting at right-angles thereto in elevation above the head of the bobbins as they are advanced beyond the stripping position, see Fig. 4, the forward edge of the flange 205 being adapted to contact with any yarn left on a bobbin after the completion of the stripping operation. Forwardly of the flange 205 is a similar flange 206 carried by the movable element of the caliper means which consists in a pivoted bar 207. The flanges 205 and 206 are preferably beveled at their ends and the flange 206 is slotted at 209 to receive screws or bolts 210 for adjustably attaching it to the caliper bar 207 so that it may be set in proper relation to the bobbin to be tested. The movable caliper bar 207 is pivoted on a stud 214 at one end of the casing 2 with its opposite free end connected to a helical spring 215 which has its opposite end anchored to the plate 203 at 216. The spring 215 urges the bar 207 laterally to carry the edge of the flange 206 toward the barrel of the bobbin being tested, a stop 217 on the bar being adapted to strike against the wall of the casing to limit its inward motion.

As has been stated, when a bobbin is completely stripped it is advanced beyond the clamping means by the engagement therewith of the next succeeding bobbin as it is moved into stripping position and the completely stripped bobbin is moved into position to drop down into the chute 10 to be removed therefrom by the magnets 24 on the conveyor belt 20. If the bobbin is not completely stripped the caliper means comes into action to cause the blades 205 and 206 to engage the yarn remaining on the bobbin and prevent it from dropping into the chute 10. Then after the next succeeding bobbin is stripped and a third bobbin advanced into the clamping means by the operation of the pusher 155 the incompletely stripped bobbin will be moved along into position to drop down into the chute 30. As this bobbin slides down the chute 30 the angular projection 31 at its end engages therewith to cause the bobbin to roll laterally off from the chute and drop down into the lower compartment or receptor 15 as indicated in Fig. 2. This last mentioned ejection of the partially stripped bobbin into the chute 30 is assisted by means of a spring 220 shown in Figs. 4 and 5. The spring 220 consists of a flat resilient strip of metal fastened at its rearward end by the bolt 192 which attaches the plate 190, previously mentioned, to the wall of the channel-iron 83. From the bolt 192 the spring 220 extends angularly in an arm formed into a V-bend 221 with a reverse bend at 222 continued in a straight extension 223. When a partially stripped bobbin is advanced beyond the caliper means to enter the chute 30 the spring 220 is first compressed or retracted by the engagement of the head of the bobbin riding across its bend 221. As this bobbin rides beyond the apex of the V-bend 221 and is engaged by its reversely-bent portion 222 the spring will react to exert a force on the side of the head of the bobbin and propel it forward with a sharp motion for insuring that it will drop down into the chute 30.

Mounted just below the rotary drum 45 is a sheet-metal member 225 fastened to the vertical portion of the bearing bracket 48 by bolts 226 projecting through slots 227 in said member.

The member 225 is formed with a horizontal plate 228 projecting forwardly across the opening in the compartment 3, see Figs. 2, 6 and 7, which is slotted to form a re-entrant slot 230. As each bobbin *b* is advanced into the clamping means its tip end is entered in the slot 230 to remain in the same relationship when the bobbin is thereafter moved into position between the caliper members. One side of the slot 230 in the plate 228 is cut away to provide a circular opening 232 terminating in a pointed prong 233 which is sharpened to provide a cutting edge. The opening 232 is adapted to catch the yarn drawing off from an incompletely stripped bobbin as the latter is advanced into the caliper device so as to sever this end which feeds back to the winding-on drum to prevent it from being drawn down through the chute 30 into the lower compartment of the casing.

Method of operation

The method of operation of the complete device is explained briefly as follows: As a bobbin *b* is ejected from the shuttle of the loom it drops down through the chute 115 into the casing 2, first passing through the bristles of the brush 105 which retains the length of yarn trailing from the bobbin. The rotation of the disk 60 revolves the fingers 100 below the bristles of the brush 105 to sweep the yarn outwardly therefrom and carry it around the plate or rest 62 and across the periphery of the drum or mandrel 45. The eventual engagement of each finger 100 with the abutment formed by the upstanding plate 193 holds the finger back to insure that it will not slide past the yarn until it has carried it across the mandrel 45 and been caught under one or more of the recessed ends of the fingers 55, see Fig. 2, as the latter are reciprocated axially of the mandrel. The end of the trailing yarn is thus caught and held to the drum 45 to cause it to wind thereon after the bobbin has been clamped in stripping position in the casing 2 therebelow. As the bobbin *b* descends in the compartment 3 of the casing 2 its butt end contacts with the counterbalanced shelf 145, see Fig. 7, to tilt the latter downwardly to the position shown in Fig. 1. The tapered barrel of the bobbin will therefore enter the opening or mouth 150 in the end of the shelf 145 to be guided and sustained in upright or vertical position as the base of the bobbin seats on the perch 120 and swings the latter downwardly into horizontal position. The shelf 145 thus acts to prevent the bobbin from being canted as it drops onto the perch 120 while the latter is tilted upwardly by its spring 136. Meanwhile, the pusher 155 is been slid to the right, as viewed in Fig. 7, but after the shelf 120 has been swung down into horizontal position the return movement of the pusher 155 will cause the finger 158 at the end of the pusher 155 to engage the forward edge of the keel 135 on the perch 120 to force the latter toward the left as its arm 123 swings about the pivot-pin 125 against the force of the spring 136. Under this action the bobbin *b* seated on the perch 120 will be caused to slide off therefrom to drop down on the floor 140 of the casing to the right of the finger 158 on the pusher 155. Consequently, as the pusher 155 slides back toward the right again, as viewed in Fig. 7, its finger 158 will engage against the rings *r* on the bobbin *b* to slide the latter along the floor 140 and advance it into stripping position as the straight portion 196 of the spring 136, see Fig. 4, engages between

the rings *r* on the head of the bobbin and the edge 194 of the clamping plate 190 also engages between the rings on the opposite side of the head. The bobbin *b* is thus clamped fixedly to be held in the position shown in Fig. 7 with the tip end of its barrel projecting up through the slot 230 in the plate 228 of the member 225. The yarn *y* will then be drawn off from the bobbin by unwinding along its barrel as it is wound up on the drum or mandrel 45 during the continuous rotation of the latter by the driving means previously described. As the mandrel 45 continues to wind the yarn on its periphery the fingers 55, see Fig. 2, are reciprocated to push the coils along the tapered portion of the mandrel and through the opening 57 in the partition 5 to discharge the waste yarn into the compartment 4.

The stripping operation is timed to normally remove all the yarn remaining in the bunch on the bobbin before the bobbin is delivered into the chute 10 to drop down into position for transfer therefrom by the conveyor belt 20 in the manner explained in our prior patent application first referred to above. The delivery of the bobbin *b* onto the chute 10 occurs when a second bobbin is released from the perch 120 and advanced by the pusher 155 to carry it into stripping position. The movement of the second bobbin into stripping position causes its head to engage the previously stripped bobbin to advance it into the caliper means for testing it to detect any yarn remaining thereon. Referring to Figs. 4 and 5, as the bobbin *b*' is advanced in this manner the edge of the fixed blade 205 and the opposite blade 206 on the spring-pressed caliper arm 207 operate to engage with the bobbin adjacent its head. Consequently, if any yarn remains on the bobbin *b*' at this point where the bunch is located the caliper means comprising the plates 205 and 206 will grip the bobbin to prevent it from dropping down into the chute 10. The length of yarn *y*' extending from the bobbin *b*' will continue to wind on the drum 45 as it enters the circular recess 232, see Fig. 6, in the edge of the plate 228 and drawing across its sharpened edge it will be severed from the bobbin while the latter is held by the caliper means.

The yarn will continue to be stripped from the next bobbin *b* which has been clamped in position and when the stripping operation is completed on this bobbin another bobbin will be displaced from the perch 120 and carried along the floor 140 of the casing 2, see Fig. 4, to advance the two bobbins *b* and *b*' in the same direction. Consequently, the second succeeding bobbin *b* if completely stripped will be advanced into position to drop into the chute 10 while at the same time it moves the incompletely stripped bobbin *b*' into position to enter the chute 30. As the bobbin *b*' compresses the spring 220 to ride past the apex of its V-bend 221 the spring will react in the manner as previously explained to forcibly propel the bobbin *b*' laterally into position to drop down into the supplementary chute 30 as indicated in Fig. 5. It has been explained that should the stripped bobbins crowd together in the space between the caliper means and jam in the opening to the chute 10 causing one of them to crowd against the edge of the chute 30, it will act to lift the latter upwardly by swinging it on its hinge 35 so that the several bobbins may be cleared automatically to drop down into the chute 10. This arrangement of the chute 30 is provided as a precaution to prevent bobbins being caught or stuck at the en-

trance to the chute 10 where it might be difficult or inconvenient to reach them to clear the device.

While the present improved device is herein illustrated and described as embodied in a preferred form of construction, it is to be understood that modifications may be made in the structure and arrangement of its parts without departing from the spirit or scope of the invention as expressed in the following claims. Therefore, without limiting ourselves in this respect, we claim:

1. A bobbin-stripper for removing the residue of yarn from spent bobbins comprising means for receiving and holding the bobbins, means for withdrawing the yarn from a bobbin to strip it, means for testing each bobbin to detect whether the yarn has been completely removed therefrom, and means to segregate bobbins on which any yarn remains after a stripping operation.
2. A bobbin-stripper for removing residual yarn from spent bobbins comprising means for receiving and holding the bobbins, means for withdrawing the yarn from a bobbin to strip it, means for testing each bobbin to detect whether the yarn has been completely removed therefrom, and means operative by said testing means to segregate incompletely stripped bobbins from those completely stripped.
3. A bobbin-stripper for removing residual yarn from spent bobbins comprising means for holding the bobbins, means for withdrawing the yarn from a bobbin, means for testing each bobbin to detect any yarn remaining thereon after a stripping operation, a conveyor for transporting stripped bobbins from the stripper, means for delivering completely stripped bobbins to the conveyor, and means for preventing delivery of incompletely stripped bobbins to said conveyor.
4. A bobbin-stripper for removing residual yarn from spent bobbins comprising means for holding the bobbins, means for withdrawing the yarn from a bobbin to strip it, means for testing each bobbin to detect any yarn remaining thereon after a stripping operation, a conveyor for transporting the bobbins from the stripper, means for delivering completely stripped bobbins to said conveyor, and means for segregating incompletely stripped bobbins to prevent them from being delivered to the conveyor with the completely stripped bobbins.
5. A bobbin-stripper for removing residual yarn from spent bobbins comprising means for receiving and holding the bobbins, means for withdrawing the yarn from a bobbin to strip it, a container for receiving stripped bobbins, means for delivering the stripped bobbins into said container, means for testing each bobbin after a stripping operation to determine if the yarn is completely removed therefrom, a container for receiving incompletely stripped bobbins, and means for delivering the incompletely stripped bobbins to the last-named container.
6. A bobbin-stripper for removing the residue of yarn from spent bobbins comprising means for receiving and holding the bobbins, means for winding on the yarn to withdraw it from the bobbins, means for delivering stripped bobbins from the stripper, means for testing each bobbin to detect any yarn remaining thereon, and means operated by said detecting means to prevent delivery of incompletely stripped bobbins with the completely stripped bobbins.
7. A bobbin-stripper for removing the residue of yarn from spent bobbins including means for

receiving and holding the bobbins, rotary means for winding on the yarn to withdraw it from the bobbins, means for caliperizing each bobbin after a stripping operation to detect any yarn remaining thereon, a container for receiving completely stripped bobbins, and means operated by the caliperizing means to prevent incompletely stripped bobbins from being delivered to the container for completely stripped bobbins.

18. A bobbin-stripper for removing the residue of yarn from spent bobbins including means for receiving and holding the bobbins, means for withdrawing the yarn from the bobbins to strip them, means for delivering stripped bobbins from the stripping means, means for caliperizing each bobbin after a stripping operation to detect any yarn remaining thereon, and means for segregating incompletely stripped bobbins to prevent them from being delivered with the completely stripped bobbins.

19. A bobbin-stripper for removing the residue of yarn from spent bobbins comprising means for receiving and holding the bobbins, means for withdrawing the yarn from each bobbin, a container for receiving stripped bobbins, means for delivering stripped bobbins into said container, means for testing each bobbin after a stripping operation to detect any yarn remaining thereon, a container for partially stripped bobbins, and means for delivering incompletely stripped bobbins into said last-named container.

20. A bobbin-stripper comprising means for holding bobbins, means for withdrawing yarn from the bobbins to strip them, a chute for receiving stripped bobbins, means for testing each bobbin to detect any yarn remaining thereon after a stripping operation, and a second chute for receiving incompletely stripped bobbins to segregate them from completely stripped bobbins.

21. In a bobbin-stripper, means for holding the bobbins therein, means for withdrawing the yarn from the bobbins to strip them, a compartment for receiving stripped bobbins, a chute for delivering stripped bobbins into said compartment, means for testing each bobbin after a stripping operation to detect any yarn remaining thereon, a compartment for receiving partially stripped bobbins, a chute for delivering partially stripped bobbins into said second-named compartment, and means for delivering completely stripped bobbins into said first-named chute and partially stripped bobbins into said second-named chute to segregate partially stripped bobbins from completely stripped bobbins.

22. A bobbin-stripper comprising a casing, means for receiving and holding the bobbins in said casing, means for withdrawing the yarn from the bobbins to denude them, a compartment in the casing for receiving stripped bobbins, means for delivering said stripped bobbins into said compartment, means for testing each bobbin before it is delivered into said compartment to detect any yarn remaining thereon, and means for preventing incompletely stripped bobbins from being delivered into said compartment to segregate them from completely stripped bobbins.

23. A bobbin-stripper comprising a casing, means for holding the bobbins in the casing, means for removing the yarn from the bobbins, a compartment in the casing for stripped bobbins, an opening for delivering stripped bobbins into said compartment, means for moving stripped bobbins into position to deliver them through said opening, means for detecting any yarn re-

maining on a bobbin following a stripping operation, a compartment for receiving incompletely stripped bobbins, an opening into said last-named compartment, and means operative to deliver incompletely stripped bobbins through the second opening into the second compartment.

24. In a bobbin-stripper, a casing having means for holding the bobbins, means for stripping residual yarn from the bobbins, a compartment in the casing for receiving stripped bobbins, resiliently-operated caliperizing means for engaging each bobbin to detect any yarn remaining thereon after a stripping operation, an opening beneath said caliperizing means for delivering completely stripped bobbins into said compartment, a second compartment in the casing for receiving incompletely stripped bobbins, and means beyond the caliperizing means for delivering incompletely stripped bobbins into said second compartment to segregate them from completely stripped bobbins.

25. A bobbin-stripper comprising a casing for receiving the bobbins, means for supporting the bobbins in the casing in position to be stripped, means for withdrawing the yarn from a bobbin to strip it, a compartment in the casing for receiving stripped bobbins, an opening beyond the bobbin-supporting means for delivering stripped bobbins into said compartment, means for moving a stripped bobbin into position to deliver it through said opening, means overlying the opening for testing each bobbin to detect any yarn remaining thereon, a second compartment in the casing for receiving incompletely stripped bobbins, an opening beyond the testing means for receiving incompletely stripped bobbins to deliver them to the second compartment, and means for transferring the bobbins from the holding means to the testing means whereby completely stripped bobbins may be caused to deliver through the opening into the first-named compartment and incompletely stripped bobbins may be forced out of the testing means for delivery through the last-named opening to the compartment for incompletely stripped bobbins.

26. In a bobbin-stripper, a casing, means for supporting bobbins in said casing, means for withdrawing the yarn from bobbins held on said supporting means, a compartment for receiving stripped bobbins, a chute for receiving stripped bobbins to deliver them to said compartment, a second compartment for receiving incompletely stripped bobbins, a chute separate from the first chute and leading to the second compartment for incompletely stripped bobbins, caliperizing means in the casing for detecting any residue of yarn remaining on the bobbins after a stripping operation, means for advancing each bobbin into the caliperizing means, an opening beneath the caliperizing means for delivering completely stripped bobbins therethrough into the first-named chute, an opening beyond the caliperizing means for receiving incompletely stripped bobbins to deliver them into the second-named chute for delivery to the second compartment, and reciprocating means for periodically feeding the bobbins from stripping position into the caliperizing means whereby completely stripped bobbins are delivered to the first-named chute and incompletely stripped bobbins transferred therebeyond into the second-named chute.

27. A bobbin-stripper comprising a casing having a compartment for receiving and holding bobbins, a second compartment arranged below

said first compartment, a third compartment arranged below the second compartment, means in the first compartment for withdrawing the yarn from the bobbins, caliper means for engaging each bobbin to detect any yarn remaining thereon, an opening beneath said caliper means, a chute leading from said opening into the second compartment, a second chute for delivering incompletely stripped bobbins into the third compartment, an opening beyond the caliper means to deliver incompletely stripped bobbins to said last-named chute, and means to move the bobbins progressively to the caliper means whereby the completely stripped bobbins will be delivered into the first-named chute and incompletely stripped bobbins will be moved beyond the caliper means for delivery into the second-named chute.

18. In a bobbin-stripper, a casing for containing and holding the bobbins, means for withdrawing the yarn from the bobbins to strip them, caliper means for testing each bobbin after a stripping operation to detect any yarn remaining thereon, a compartment for receiving stripped bobbins, means for delivering completely stripped bobbins from the caliper means into said compartment, a compartment for incompletely stripped bobbins, means for advancing the bobbins into the caliper means, means for delivering completely stripped bobbins from the caliper means to the first-named compartment and advancing incompletely stripped bobbins beyond the caliper means for delivery to the second compartment to segregate them from the completely stripped bobbins, and a conveyor having means entering the compartment for completely stripped bobbins and attaching the bobbins thereto to transport them from the stripper.

19. In a bobbin-stripper having means for receiving and holding the bobbins to be stripped, a rotary mandrel for winding on the yarn to withdraw it from the bobbins, a rotary member located above said mandrel, means for driving said mandrel and rotary member, and resilient fingers carried by said rotary member to adapt them to engage the yarn trailing from a bobbin entering the stripper and carry it to the mandrel for attachment thereto.

20. In a bobbin-stripper, the combination of means for holding bobbins to strip the yarn therefrom, a rotary mandrel for winding on the yarn, a member arranged above said mandrel and rotatable on an axis normal to that of the mandrel, and resilient fingers projecting from said rotary member to adapt them to sweep against the length of yarn trailing from a bobbin to carry it across the mandrel for attachment thereto.

21. In a bobbin-stripper comprising a casing for receiving and holding the bobbins to be stripped, a rotary mandrel in said casing for winding on the yarn to withdraw it from the bobbins, a brush above said mandrel having its bristles arranged to engage the yarn trailing from a bobbin as it descends into the casing, a rotary member above the mandrel, resilient fingers carried by said rotary member, a rest beneath the fingers, and an abutment adapted to engage said fingers during their rotation by said member to cause them to flex as they wipe thereagainst, said resilient fingers acting to sweep the yarn out of the brush and across the mandrel for attachment thereto.

22. In a bobbin-stripper of the type indicated, the combination of a rotary mandrel for winding

on the yarn to withdraw it from bobbins held in the stripper, a plate overlying said mandrel, a member rotatable above said plate, resilient fingers carried by said member extending radially outward therebeyond to revolve above the plate, and means to rotate said member to cause the fingers to carry the yarn trailing from a bobbin around the plate and across the mandrel for attachment thereto.

10 23. A bobbin-stripper for removing residual yarn from spent bobbins comprising means for fixedly holding the bobbins, means for withdrawing the yarn from a bobbin to strip it, a perch for receiving the bobbin prior to its entrance into the holding means, and a hinged shelf above the perch adapted to interrupt the descent of the bobbin onto the perch, said shelf having means at its end engageable with the barrel of the bobbin as its butt end moves down onto the perch to sustain the bobbin in erect position.

15 24. A bobbin-stripper for removing residual yarn from spent bobbins comprising means for fixedly holding the bobbins, means for withdrawing the yarn from a bobbin to strip it, a perch for receiving the bobbin prior to its entrance into the holding means, a pivoted shelf above the perch, a weight for counterbalancing said shelf to maintain it in horizontal relationship, said shelf being adapted to be struck by a bobbin during its descent to tilt said shelf downwardly, and means carried by the shelf for engaging the barrel of the bobbin as the latter moves down onto the perch to sustain it in erect position.

20 25. A bobbin-stripper for removing residual yarn from spent bobbins comprising means for fixedly holding the bobbins, means for withdrawing the yarn from a bobbin applied to the holding means, a perch for receiving the bobbin thereon prior to applying it to the holding means, a shelf pivoted above said perch, means for holding said perch normally in horizontal relationship, an arm extending downwardly from the perch in inclined relation thereto, and an opening at the end of the shelf for receiving the barrel of the bobbin to guide it during its fall onto the perch, said arm on the shelf adapted to engage against the side of the casing to maintain the shelf in position with its opening engaged with the barrel of the bobbin to maintain it in erect position seated on the perch.

25 26. A bobbin-stripper comprising means for fixedly holding the bobbins, means for engaging the bobbins with the holding means, means for withdrawing the yarn from a bobbin held in the holding means to strip it, means for caliper the bobbins after a stripping operation to detect any yarn remaining thereon, means for advancing the bobbins from the holding means into the caliper means, and means for engaging the length of yarn being withdrawn from an incompletely stripped bobbin in the caliper means to sever the yarn therefrom.

30 27. A bobbin-stripper for removing residual yarn from spent bobbins comprising means for holding the bobbins, means for withdrawing the yarn from a bobbin to strip it, means for testing each bobbin after a stripping operation to detect any yarn remaining thereon, and means operative during the testing operation to sever the length of yarn being withdrawn from a bobbin containing any excess of yarn thereon.

35 28. A bobbin-stripper for removing residual yarn from spent bobbins comprising means for holding the bobbins, means for withdrawing the

17

yarn from a bobbin to strip it, means for testing each bobbin to detect any yarn remaining thereon after a stripping operation, a container for completely stripped bobbins, means for delivering completely stripped bobbins into said container, a second container, means for delivering incompletely stripped bobbins into said second container, and means operative during the testing of an incompletely stripped bobbin to sever the length of yarn being withdrawn therefrom.

29. A bobbin-stripper for removing residual yarn from spent bobbins comprising means for holding the bobbins, means for withdrawing the yarn from a bobbin to strip it, means for testing each bobbin to detect any yarn remaining thereon after a stripping operation, a conveyor for transporting stripped bobbins from the stripper, means for delivering completely stripped bobbins to said

18

conveyor, means for segregating incompletely stripped bobbins to prevent them from delivering to the conveyor, and means between the withdrawing means and the bobbin for severing the length of yarn being withdrawn from an incompletely stripped bobbin.

30. A bobbin-stripper for removing the residue of yarn from spent bobbins comprising means for withdrawing the yarn from a bobbin to strip it, means for testing each bobbin to detect whether the yarn has been completely removed therefrom, and means to segregate bobbins on which any yarn remains after a stripping operation.
